CANNON PINION INDENTING FIXTURE

Gilbert C. Childs, III, Lancaster, Pa., assignor to
Hamilton Watch Company, Lancaster, Pa.

Application March 2, 1949, Serial No. 79,229

2 Claims. (Cl. 153—48)

1

This invention relates to a power machine for dimpling a cannon pinion.

The cannon pinion which is that part of the watch which carries the hands must be held frictionally on the center staff so that it will turn with the center staff and yet loosely enough so that the hands may be set by means of the winding stem. It must also be capable of easy removal in the necessary cleaning and repair of the watch. This friction fit is generally brought about by dimpling diametrically opposite points in the cylindrical wall of the cannon pinion. Previously this dimpling has been done by hand and is one of the more costly operations in the making of watch parts. This invention relates to a power press for dimpling the cannon pinion and a single unskilled operator can in a day's work do many times more than a skilled operator did previously.

The object of the present invention is to provide a simple power press which is capable of certain minute adjustments to provide for the very accurate dimpling of the cannon pinion.

A still further object of the present invention is to provide self-aligning and self-centering features which will automatically compensate for slight errors in the work.

A further object of the present invention is to provide a machine which will do with unskilled labor what was previously done by hand through highly skilled labor.

The invention is illustrated in the accompanying drawings in which:

Figure 1 is a perspective view of the entire assembly with parts broken away.

Figure 2 is a top plan view with parts broken away.

Figure 3 is a cross-sectional view taken through the dimpling anvils.

Figure 4 is an enlarged cross-section showing the anvils in engagement with the cannon pinion.

Figure 5 is a greatly enlarged view showing the cannon pinion mounted on the center staff, together with the hands and dial.

Figure 6 is a cross-sectional view on line 6—6 of Figure 3.

The machine comprises a base 8 having legs or standards 9 for bench mounting. Mounted on the base at the rear is an air cylinder 10 connected to an air line 11 by means of the hose 12 and operated through the foot valve 13. This construction is optional, any of the standard air cylinders in use on the market being suitable for the job.

5 Mounted in parallel relation in the base 8 in a recessed portion 14 of the base 8 are parallel rods 15 which carry a cross-head 16 slidably mounted thereon. A plunger 17 connected to the piston of the air cylinder extends into a cut out portion 18 of the cross-head and serves to transmit the force of the air cylinder to the cross-head. Sleeves 19 serve as bearings for the cross-head in its operation on the rods 15 and are replaceable after being worn to insure the true straight line operation of the cross-head.

The cross-head 16 is formed with forwardly and outwardly diverging arms 20 slotted at their outer ends as at 21 to provide the bearings for pins 22. Links 23 are carried by the pins 22 and extend inwardly of the extended arms, bearing against the outer plates 24 along the forward edge 25. A block portion 26 of the base 8 is bored at 27 to receive the cylinders 28 which are urged outwardly from the center by the compression springs 29. The top of the block 26 is milled to receive the slides 30 which are connected to the cylinders 28 by pins 31 passing through the slot 32 between the milled portion 20 and the holes 27. The slides 30 are connected at their outward extremities to the links 23 by pins 33 so that the outward urging action of the compression springs 29 is transferred through the pins and the slides to the links 23 and together with a spring (not shown) in the air cylinder move the cross-head and its attached air piston to initial position.

A top plate 34 is secured to the block 26 and serves as a top bearing for the slides 30 in the milled portion of the block 26. The block 26 is further milled at the center portion as at 35 to form a recess for the central fixture pin 36. The top plate 34 is cut to conform to this recess 35 so that access to the fixture 36 may be had directly from above and the front of the machine.

Extending up through the approximate center of recess 35 is a pin fixture 36, the projecting end of which is located directly between the inward ends of the slides 30. This fixture is adapted to receive the workpiece, or cannon pinion on its upper projecting end, the lower portion of the pin fixture 36 is enlarged to fit the tube bearing 37 which is fixed in the block 26 and is provided with external threads at its lower end to receive an adjusting nut 38 held in position by screws 39 and plates 40. The enlarged lower portion 41 of the pin fixture is a tight friction fit into the tube bearing 37 and is further enlarged to provide a cap 42 having a shoulder portion which 55 bears against the end of the tube 37. This per-

mits the nut 38 to move the tube and pin fixture as a unit for vertical adjustment. After the desired adjustment of the fixture is obtained, a set screw 54 shown in Figures 1 and 2 is turned in against the tube 37 securely locking it in the desired position. Directly above the enlarged portion 41 the pin fixture is sectionally reduced to provide a flexing portion 43. The pin fixture 36 is of resilient material and the flexing portion 43 together with the reduced upper portion 44 of the pin permits lateral movement of the pin for purposes hereinafter explained.

Referring particularly to Figure 6, a cross-section is shown showing the reduced portion 43 of the fixture 36. This view is taken looking up in the direction of the arrows on the line 6-6 and shows the clearance of the upper part 44 of the fixture which permits slight movement of the upper part of the fixture with the attached cannon pinion. The shape of the flexing portion 43 permits movement in the direction of the slides 30 while preventing any lateral movement of the fixture with relation to the slides.

The ends 45 (Figure 4) of the slides 30 are U-shaped as at 46 (Figure 1) to support anvils 47, the anvils being seated in curved portions 48 of the U-shaped ends of the slides 30.

Referring to Figure 5 which shows a cannon pinion 49 mounted on a center staff 50, the enlarged view definitely shows the reason and function of the dimples 51 made in the cannon pinion. The cannon pinion must turn frictionally with movement of the center staff 50 and yet be capable of turning on the center staff when it is desirable to set the hands. The minute wheel is turned by the center staff through the cannon pinion which in turn through the hour wheel turns the hour hand. This cannon pinion must be capable of easy removal in case of cleaning and must be both frictionally held to the center staff and free to turn on it. The amount of indentation of the dimple is then extremely critical and where interchangeable parts are made, so that anyone of a thousand watches, the degree of tolerance allowable in this dimple is extremely small, amounting to less than $1/10,000$ of an inch.

To accomplish this minute measurement an adjustable anvil 52 (Figure 2) is mounted on the cross-head 16 and contacts the rearward edge of the block 24. In this manner the forward motion of the cross-head can be accurately regulated so that the inward movement of the anvils 47 can be accurately determined. A set screw 53 securely holds the anvil 52 in the desired adjusted position.

The operation of the machine may be briefly summarized in that the operator places a cannon pinion with the gear 49 down over the projecting end of the pin fixture 36. Operation of the valve 13 causes the air cylinder 10 to function, moving the cross-head 16 forward. This forward movement of the cross-head is transmitted through the links 23, their forward edges 25 bearing against the plates 24 and moving with slides 30 and their anvils 47 inward in extremely fast movement. This movement which is too fast for the eye to follow brings the anvils to the position

shown in Figure 4 indenting the dimples 51 into the cannon pinion. Retraction of the anvils 47 and their slides 30 is accomplished by means of the compression springs 29 acting against the cylinders 28 and through the pins 31 to the slides 30.

What is claimed is:

1. A cannon pinion indenting machine comprising a pair of anvils mounted for sliding opposing movement relative to each other, means for operating said anvils, a fixture for supporting a cannon pinion between said anvils, said fixture being formed with a resilient portion permitting movement in the direction of the sliding movement of said anvils while furnishing stable support to movement lateral of said anvil movement, whereby the indenting action of the anvils on the cannon pinion is simultaneously directed at diametrically opposite points on the cannon pinion.

2. A cannon pinion indenting machine comprising a base, a pair of parallel rods carried by said base, a cross-head mounted on said rods for sliding movement, means for operating said cross-head, an adjustable stop for limiting the travel of said cross-head, means for locking the stop in adjusted position, a pair of slides mounted in said base for movement at right angles to said cross-head, means connecting said cross-head to said slides whereby movement of the cross-head is transferred to the slides, a tube slidably mounted in said base at right angles to said slides, an adjusting nut rotatably carried by said base and threaded onto said tube to provide means for vertically adjusting the tube, a cannon pinion supporting fixture frictionally held at its lower end in said tube, the upper end being reduced to allow a certain limited movement of the fixture within the tube, said fixture between the upper and lower portions being of narrowed rectangular cross-section to provide flexure in the direction of movement of the slides while insuring stability at right angles to such movement, means for locking said tube in adjusted position so that cannon pinions carried by said fixture in said tube can be successively placed on said fixture and bear exactly the same relative position to said slide, anvils carried at the opposing ends of said slides and adapted to simultaneously contact opposing sides of the cannon pinion, the narrowed flexible portion of said fixture providing automatic means for insuring simultaneous contact of the anvils.
